UNITED STATES PATENT OFFICE

130,076

DESIGN FOR AUTOMOBILE COOLER

Frederick J. Vondenbosh, Los Angeles, Calif.

Application April 30, 1940, Serial No. 92,037

Term of patent 3½ years

To all whom it may concern:

Be it known that I, Frederick J. Vondenbosh, a citizen of the United States, residing at Los Angeles, in the county of Los Angeles and State of California, have invented a new, original, and ornamental Design for an Automobile Cooler, of which the following is a specification, reference being had to the accompanying drawings, forming part thereof.

Fig. 1 is a front perspective view of an automobile cooler showing my new design.

Fig. 2 is a plan view.

Fig. 3 is a rear perspective view.

I claim:

The ornamental design for an automobile cooler, as shown.

FREDERICK J. VONDENBOSH.
